UNITED STATES PATENT OFFICE

128,643

DESIGN FOR A BEVERAGE FAUCET

John E. Rosander, Minneapolis, Minn.

Application April 25, 1941, Serial No. 100,621

Term of patent 14 years

To all whom it may concern:

Be it known that I, John E. Rosander, a citizen of the United States and residing in the city of Minneapolis, county of Hennepin, and State of Minnesota, have invented a new, original, and ornamental Design for a Beverage Faucet, of which the following is a specification, reference being had to the accompanying drawing, forming a part thereof, wherein:

Fig. 1 is a perspective view of a beverage faucet, showing my design.

Fig. 2 is a side elevational view; and
Fig. 3 is a top plan view.

The dominant feature of the design resides in the portion of the beverage faucet shown in full lines.

I claim:

The ornamental design for a beverage faucet, as shown and described.

JOHN E. ROSANDER.
